UNITED STATES PATENT OFFICE

FREDERICK H. JOHNSON, OF SOUTH PASADENA, CALIFORNIA

SPRINKLER HEAD

Application filed May 6, 1925. Serial No. 28,333.

This invention relates to sprinkler heads, and more particularly to half spray nozzles or heads which are adapted for use close to walks or the like for the purpose of spraying from the walks or the like without throwing the spray upon the walks or the like.

An object of this invention is to provide a half spray nozzle or head which includes a body having a bore extending therein, which bore is substantially tangent to and in advance of the diameter of the said vertical body, and which terminates in a spray chamber formed in the head so that as the spray is formed in the head it is thrown from the nozzle as a fan, or substantially half circular form in advance of the spray chamber.

Other objects and advantages of this invention will be apparent from the following detailed description of a preferred embodiment thereof as illustrated in the accompanying drawings:

In the drawings:

Fig. 1 is a front elevation of a sprinkler head embodying this invention.

Fig. 2 is a side elevation thereof, looking from right to left in Fig. 1.

Fig. 3 is a central sectional side elevation taken on the line 3—3 of Fig. 1.

Fig. 4 is a top plan view taken substantially on the line 4—4 of Fig. 1.

Fig. 5 is a sectional top plan view taken substantially on the line 5—5 of Fig. 2.

Fig. 6 is a view similar to Fig. 5, illustrating the valve partially closed.

In the preferred embodiment of this invention illustrated in the accompanying drawings 1 illustrates the sprinkler head body which has a reduced portion 2 and threads 3 so that the same may be secured in position in sprinkler system apparatus. The body 1 is preferably formed with a hexagonal portion 4 so as to permit gripping thereof in screw threading the same in and from position. A bore 5 is formed in the body 1 from its lower end and terminates in the spraying chamber 6. The chamber 6 has a downwardly extending lip 7 curved throughout its length as is particularly illustrated in Fig. 1 and a downwardly and forwardly inclined curved recess 8 at its lower portion. The chamber

6 is of greater cross sectional area than the bore 5 for the purpose of preventing sand from becoming lodged therein from the bore 5 to stop the function or proper functioning thereof.

An important feature of this invention lies in the provision of a spray chamber 6 that is of approximately semi-circular horizontal cross-section and over which the upper lip 7 extends which is likewise of semi-circular horizontal cross-section.

The back wall 9^a of the recess 8 is preferably straight and its position is preferably upon the plane passed through the central axis of the body 1 so that the recess 8 is in vertical section practically semicircular. A head 9, having a bore 10 therethrough is spun onto the body 1 at its lower end so as to provide a small shoulder 11 which is retained in position by means of the lip 12. This manner of uniting the head 9 to the body 1 provides a fluid tight connection between the body 1 and the head 9. The bore 10, like the bore 5, is formed in an off-center position.

The back-wall 9^a is substantially tangent to the bore 5 of the body 1 and extends laterally from the said bore 5. The formation of this back-wall 9^a, which extends a substantial distance from the bore 5, permits the sprinkler head to form an accurate half-spray, and the formation of the bore 5 in an off-center position in the body 1 permits the formation of this back-wall 9^a of such lateral extension that the same will present a substantial barrier to the water and the same will not be thrown rearwardly from the sprinkler head so as to form a spray which is of accurate horizontal semi-circular cross-section.

A groove 13 is formed in the lower portion of the head 9 so that a sharp edged instrument may be inserted therein to turn the head 9 to properly adjust communication between the bores 10 and 5 into some such position as is illustrated in Fig. 6. By this manner of construction, when the head 9 is turned to the position illustrated in Fig. 6, the same will remain in that position and the volume of water permitted to flow through the port 5 may be accurately regulated thereby so that

the width or reach of the spray issuing from the recess 6 will be determined.

From the foregoing it will be apparent that I have provided an extremely simple form of valve and sprinkler head construction that is extremely well adapted to carry out the functions for which it is designed.

Having fully described the preferred embodiment of this invention, it will be understood that I do not wish to be limited to the exact construction herein set forth which may, obviously, be varied without departing from the spirit of the appended claim.

I claim:

A half-spray nozzle comprising a body cylindrical in form, having a bore extending longitudinally therein, said bore being tangent to and in advance of the diameter of said vertical body, and being tangent to the longitudinal axis of the body, and a lateral slot 20 in said body intersecting the end of said bore and terminating in a substantially straight rear wall that is substantially tangent to the bore and terminates at the periphery of said body.

Signed at Los Angeles, California, this 27th day of April 1925.

FREDERICK H. JOHNSON.
